UNITED STATES PATENT OFFICE.

JAMES WEST, OF BROOKLYN, NEW YORK.

DESIGN FOR A FONT OF PRINTING-TYPE.

SPECIFICATION forming part of Design No. 15,923, dated March 3, 1885.

Application filed January 31, 1885. Term of patent 7 years.

To all whom it may concern:

Be it known that I, JAMES WEST, of Brooklyn, Kings county, New York, have invented and produced a new and original Design for a 5 Font of Printing-Type, of which the following is a specification.

The nature of my design is clearly shown in the accompanying typographic impression, to which reference is made; and it consists of 10 a letter the upper portion of which is Roman in character, while the lower portion is Gothic in character, ornamented by a groundwork of light curved line character.

The character of the design is preserved in the symbols & and dollar-mark, the numerals, and punctuation-marks. 15

I claim as new—

The design for a font of printing-type, substantially as shown and described.

JAMES WEST.
